UNITED STATES PATENT OFFICE.

ALDEN M. DRAKE, OF WORCESTER, MASSACHUSETTS, ASSIGNOR TO HEALD MACHINE COMPANY, OF WORCESTER, MASSACHUSETTS, A CORPORATION OF MASSACHUSETTS.

GRINDING-WHEEL SHAFT AND BEARING.

1,181,999.

Specification of Letters Patent.

Patented May 9, 1916.

Application filed September 15, 1915. Serial No. 50,884.

To all whom it may concern:

Be it known that I, ALDEN M. DRAKE, a citizen of the United States, residing at Worcester, in the county of Worcester and 5 State of Massachusetts, have invented a new and useful Grinding-Wheel Shaft and Bearing, of which the following is a specification.

This invention relates to a grinding wheel 10 shaft and bearings and particularly to improved devices for moving the shaft longitudinally to adjust the grinding wheel relatively to the work.

While my invention is capable of general application, I have shown it herein as embodied in a surface grinding machine in which a cup grinding wheel is used. In this type of machine, the grinding wheel is carried at the lower end of a vertical wheel 20 shaft and, as commonly constructed, the wheel shaft is mounted in bearings in a vertically movable wheel slide. This wheel slide is necessarily of substantial weight and bodily adjustment thereof is not satisfactory for the final vertical adjustment of the 25 grinding wheel.

It is the principal object of my invention to provide improved devices for securing close vertical adjustment of the grinding wheel relatively to the work independently of the adjustment of the slide.

With this object in view, one feature of my invention relates to the provision of a supplementary adjusting mechanism by 35 which the grinding wheel shaft may be adjusted relatively to the wheel slide.

Further features of my invention relate to the provision of means for preventing back-lash between the wheel shaft and slide, 40 and to means for forcing the wheel shaft at all times vertically upward into firm engagement with the wheel slide.

My invention further relates to certain arrangements and combinations of parts 45 which will be hereinafter described and more particularly pointed out in the appended claims.

A preferred form of my invention is shown in the drawings in which— 50 Figure 1 is a vertical sectional view of a portion of a wheel slide with my improved shaft and bearing mounted thereon; Fig. 2 is a detail side elevation of a portion of the adjusting nut, looking in the direction of

the arrow 2 in Fig. 1, and Fig. 3 is a partial end elevation of a surface grinding machine, showing the mechanism for manually moving the adjusting nut.

Referring to the drawings, I have indicated in Fig. 3 a surface grinding machine 60 having a base 10, a standard 11, and a work table 12, all of the usual form. A wheel shaft 13 (Fig. 1) is mounted in bearings in a wheel slide 14 which is vertically adjustable upon ways 15 formed on the front face 65 of the standard 11. The mechanism (not shown) for vertically adjusting the wheel slide and for retaining the same in adjusted position upon the standard 11 may be of any suitable or convenient form and forms no 70 part of my present invention.

The grinding wheel shaft 13 is driven by a belt upon a pulley 16 and at its lower end supports a cup grinding wheel 17, cemented or otherwise secured in a ring 18 which is 75 fastened to a face plate 19 by screws 20. The face plate 19 is keyed to the tapered lower end of the shaft 13 and is secured thereon by a binding nut 21, all of the usual construction.

The shaft 13 is mounted to rotate in upper and lower ball thrust bearings 210 and 211, the outer portions of which are carried by a sleeve 22. The outer portion of the lower bearing 210 engages a shoulder 22^a 85 upon the sleeve 22, and the outer portion of the upper bearing 211 engages a shoulder 22^b upon the sleeve 22. These parts are held closely in engagement with each other by a series of springs 23 mounted in recesses in a collar 24 slidable but non-rotatable upon the shaft 13. The collar 24 furnishes a support for the inner portion of the upper ball bearing 211 and is forced yieldingly downward by the downward 90 thrust of the springs 23.

The upward thrust of the springs is communicated through sliding pins 25 to a collar 26 threaded to the shaft 13 and secured in adjusted position thereon by a set screw 100 27. Through the collar 26 and the shaft 13, the upward thrust of the springs 23 is transmitted to the face plate 19 and thus forces the lower thrust bearing 210 upward into engagement with the shoulder 22^a. At the 105 same time the weight of the shaft 13 and wheel 17 and the downward thrust of the springs 23 moves the sliding collar 24 down-

wardly until the upper thrust bearing 211 firmly engages the shoulder 22^b, thus eliminating all back-lash between the shaft 13 and the sleeve 22.

5 The sleeve 22 is keyed to slide vertically in a projecting portion of the slide 14. In order to provide for a close vertical adjustment of the grinding shaft and wheel, the sleeve 22 is screw-threaded upon its outer 10 cylindrical surface, and an adjusting nut 28 is mounted between shoulders in a recess in the slide 14 to coöperate therewith.

The nut 28 is provided with gear teeth 29 upon its outer surface and may be conveniently adjusted by a hand wheel 30 (Fig. 3), the connection from the hand wheel to the adjusting nut including a shaft 31, bevel gears 32 and 33, a vertical shaft 34 keyed to the gear 33 but slidable therein, a gear 35 carried by the shaft 34, and an idle gear 36 meshing with the gear 35 and also with the teeth 29 upon the adjusting nut 28.

To secure a close fit between the nut 28 and the threads upon the sleeve 22, I form 25 the nut in two parts 28^a and 28^b, said parts being capable of limited angular adjustment, and being secured in adjusted position by a screw 37 extending through a horizontal slot 38 (Fig. 2) in the portion 28^a of 30 the nut 28, and threaded into the portion 28^b thereof.

In order to take up the back-lash between the nut 28 and the slide 14, I provide a series of springs 40 inserted in recesses in 35 the nut portion 28^b and engaging at their lower ends a bearing ring 41. The ring 41 is rotatable with the nut 28, being connected thereto by a stud 42 mounted in the ring 41 and extending upwardly into a hole 43 in 40 the nut portion 28^b. The action of the springs 40 is similar to that of the springs 23 previously described, the upward thrust of the springs forcing the nut 28 firmly into engagement with the upper shoulder of the 45 wheel slide 14.

Having thus described the details of my invention the operation thereof will be apparent. The rough vertical adjustment of the cup wheel 17, relatively to the work carried by the table 12, may be secured by adjusting the wheel slide 14 upon the standard 15. Having brought the grinding wheel to its appropriate working position by this means, the final close adjustment may 50 be secured by angular movement of the adjusting nut 28, such movement being conveniently obtained by the use of the hand wheel 30 and the connections described. The springs 40 force the nut firmly into engagement with the upper shoulder of the slide 14 and the springs 23 force the grinding wheel shaft and its associated bearings firmly into engagement with the shoulders of the sleeve 22. I thus provide a convenient arrangement for close and accurate ver-

tical adjustment of the wheel shaft and I at all times take up the back-lash between the parts so that the grinding wheel will be firmly supported against the upward thrust of the work.

Having thus described my invention, it will be evident that changes and modifications can be made therein by those skilled in the art without departing from the spirit and scope thereof as set forth in the claims, 75 and I do not wish to be otherwise limited to the details herein disclosed but

What I claim is:—

1. In a grinding machine, in combination, a standard, a vertically movable wheel slide 80 supported on said standard, a wheel shaft mounted in bearings in said slide, a sleeve supporting said bearings, said sleeve being screw-threaded upon its outer cylindrical surface and being vertically movable but 85 non-rotatable in said slide, a nut mounted in said slide, and means to rotate said nut to thereby adjust said sleeve vertically in the slide.

2. In a grinding machine, in combination, 90 a standard, a vertically movable wheel slide supported on said standard, a wheel shaft mounted in bearings in said slide, a sleeve supporting said bearings, said sleeve being screw-threaded upon its outer cylindrical surface and being vertically movable but 95 non-rotatable in said slide, a nut rotatable between upper and lower shoulders on said slide, means to rotate said nut, and means to force said nut yieldingly upward against 100 the upper shoulder.

3. In a grinding machine, in combination, a standard, a vertically movable wheel slide supported on said standard, a wheel shaft mounted in bearings in said slide, a sleeve supporting said bearings, said sleeve being screw-threaded upon its outer cylindrical surface and being vertically movable but 105 non-rotatable in said slide, a nut rotatable between upper and lower shoulders on said slide, a plurality of coiled springs seated in recesses in said nut and a bearing ring rotatable with said nut and forced by said springs into engagement with said lower shoulder, the reaction of said springs on 115 said nut forcing the nut upwardly into engagement with the upper shoulder.

4. In a grinding machine, in combination, a standard, a vertically movable wheel slide supported on said standard, a wheel shaft 120 mounted in bearings in said slide, a sleeve supporting said bearings, said sleeve being screw-threaded upon its outer cylindrical surface and being vertically movable but non-rotatable in said slide, a nut formed in 125 two relatively movable parts, means to hold said parts in adjusted position, one of said parts engaging the upper shoulder on said slide, and the other part having a plurality of springs seated and axially extensible 130

therein, and a bearing ring rotatable with said nut and pressed by said springs into engagement with the lower shoulder.

5. In a grinding machine, in combination, a standard, a vertically movable wheel slide supported on said standard, a wheel shaft mounted in bearings in said slide, an externally threaded sleeve supporting said bearings, yielding means to force said bear-

ings upwardly into close engagement with 10 said sleeve, a nut for adjusting said sleeve axially, said nut being rotatable between upper and lower shoulders on said slide, and yielding means to force said nut into engagement with said upper shoulder. 15

In testimony whereof I have hereunto set my hand.

ALDEN M. DRAKE.
